UNITED STATES PATENT OFFICE.

FELICE GILARDINI, OF TURIN, ITALY.

METHOD OF MANUFACTURING BELTS.

1,360,923.

Specification of Letters Patent. Patented Nov. 30, 1920.

Application filed April 10, 1919. Serial No. 289,094.

To all whom it may concern:

Be it known that I, FELICE GILARDINI, a subject of the King of Italy, residing at Turin, Italy, have invented certain new and useful Improvements in Methods of Manufacturing Belts; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to the method of manufacturing belts for the transmission of motion in machinery, and has for its object to produce belts that are not liable to stretch during use and possessing greater 20 tensile strength than belts heretofore known.

The present application is a continuation in part of my application filed April 6, 1918, Serial Number 227051 now Patent 1,309,066, dated July 8, 1919, and the method consists 25 chiefly in tanning the hides or skins only in successive sections separated by narrow parts, which are unprepared but highly compressed, the tanning and compression operation being effected while the hides or 30 skins are kept under the utmost tension. It would also be possible to obtain a belt having the above-named qualities by superficially tanning the parts extending between the tanned ones with fats or the like, in 35 order that the belt may be used advantageously even in wet places. For the same purpose, it would be advantageous to soak the skin, before stretching it, in a tan liquor, preferably constituted by a mineral solution, 40 which penetrates in a very small quantity the flesh as well as the hair side of the skin.

This belt is illustrated, by way of example and diagrammatically in the annexed drawing.

45 Figures 1 and 2 are respectively a plan view and a section of the belt, in which the tanned parts are circular.

Figs. 3 and 4 are similar views of a belt of the present type, in which the tanned parts are of rectangular form.

50 Figs. 5 and 6 show belts of the present type put on a pulley in order to show their advantages.

Fig. 7 is a diagrammatic view of a hide 55 stretching apparatus, on which is mounted

a frame; Fig. 8 is a diagrammatic view of a series of frames immersed in a tanning vat; Fig. 9 is a diagrammatic section of a tanning drum, and Figs. 10 and 11 are respectively, a section and a plan view of a 60 hide portion stretched between grates.

The rectangular piece of the skin called the "butt" is used for this belt as it is the general rule in the processes already known when belts of good quality are to be produced. Said butt is obtained in the usual manner by cutting a rectangular piece in the best and central part of the raw skin.

The butt, either in one piece or cut, as it is preferable, in two, three or more lengths, 70 is placed in a stretching device, drawn to the utmost tension and kept in this condition.

An apparatus of this type is shown diagrammatically and by way of example in 75 Fig. 7. Said apparatus consists of a frame having two heads 1 and 2 suitably secured to a body (not shown) and two guides 3 and 4 attached to the corresponding ends of the heads. On these guides slides a cross-bar 5 provided centrally with a screw 6 and hook 7. The screw 6 passes through a hole 8 in the head 2 and the nut 9, provided with handles 10, is screwed on the screw 6. The head 1 is also provided with a central hook 7. The hide-stretching device is attached to the hooks 7 by means of eyelets 11. Said device consists of a fixed and a movable clamp, 12 and 13, the latter of which is adapted to slide along two guides 14 as far 80 as the clamp 12. The hide 15 is secured in the clamps by means of winged nuts 16, it is then stretched by screwing the nut 9. The clamp 13 is fixed by means of the set-screws 17; the device is detached from the apparatus and on the two sides of the well stretched hide are disposed the grates (Figs. 10 and 11) provided with corresponding holes 19, which are compressed by means of the bolts 20 or other suitable means. The 90

hides compressed between the grates are then introduced into the tanning solution in vats 21 (as shown in Fig. 8) where 22 shows diagrammatically the device supported by cross-bars 23, or, in order to accelerate the 100 operation, in drums as shown in cross-section in Fig. 9. 24 is the drum, on the bottoms of which is conveniently supported the axle 25, whereon are mounted within the drum two or more wheels 26. On the rim 105 110

and hub of said wheels and in correspondence with the bisector of the angle formed by two spokes 27 are provided the notches 28 in which the projecting ends of the guides 14 are held by means of suitable clamps.

When the tanning operation has been effected, according to any desired process, the washing with running water will be carried on, the hides being still kept in the stretched condition; thereupon the gradual drying operation will take place, further the dressing, and then the treatment with grease, using the usual substances (for instance oils, degras, tallow, and the like), either by soaking or preferably by stuffing or in any other known way. The hides are then slowly dried until quite dry and finally taken off the frame and hammered, or preferably rolled. The manufacture of belts obtained from this leather will then take place in the usual way, cutting the butts in more or less wide strips according to the desired thickness and size of the belts and effecting the several following well known operations.

The belts obtained by this process are therefore constituted by tanned parts separated by unprepared but strongly compressed parts. Now it is well known that the unprepared but strongly compressed hide or skin acquires a high resistance, equal to 7 or 8 k. per mm.² of breaking load, while the tanned skin has a maximum tensile strength of 3 to 3½ k. per mm.², and undergoes a remarkable elongation. As the tanned parts in this belt are separated by unprepared ones, the belt will not be stretched in a noticeable degree, owing to the stiffness of the unprepared parts, while the pliancy of the tanned parts will allow the fitting of the belt on the pulleys, as it appears clearly from Figs. 5 and 6; moreover, the belts have a greater tensile strength than the belts known heretofore.

This belt shows moreover, the advantage of a proper grip of the pulley produced by the tanned parts which are of greater thickness than the unprepared ones (see Figs. 2, 3, 5, and 6); its working may be compared to a Gall's chain or similar chain having numerous links joined side by side, the stiff unprepared parts would correspond to the links of the chain and the supple parts to the joints. The roughness of the belt surface that lies on and adheres to the

pulley only with the tanned parts produces the proper grip aforesaid.

Hides or skins tanned according to this process may be used for any other purpose beyond that here mentioned for the manufacture of belts.

I claim—

1. The method of manufacturing leather belts which comprises tanning successive sections of the hide while subjecting sections between the sections being tanned to compression.

2. The method of manufacturing leather belts which comprises tensioning the un-tanned hides, placing sections of the tensioned hide under pressure, and tanning the unpressed sections of the hide.

3. The method of manufacturing leather belts, which comprises subjecting the raw hide to tension, compressing the tensioned hide between grates, and tanning the hide through the openings of the grate.

4. The method of manufacturing leather belts, which comprises, subjecting the raw hide to tension, compressing portions of the tensioned hide, subjecting the unpressed portions of the hide to a tanning solution, and subjecting the compressed portions to a superficial tanning.

5. The method of manufacturing leather belts, which comprises subjecting the raw hide to tension, compressing portions of the tensioned hide, subjecting the unpressed portions of the hide to a tanning solution, and subjecting the compressed portions to a superficial tanning on both sides.

6. The method of manufacturing leather belts which comprises soaking the butt in a mineral solution, cutting the soaked butt into strips, stretching the strips, pressing the stretched strips between grates, and tanning the strips through the openings of the grate.

7. The method of manufacturing leather belts which comprises soaking the butt in a mineral solution, cutting the soaked butt into strips, stretching the strips, pressing the stretched strips between grates, tanning the strips through the openings of the grate, removing the grates, and subjecting the compressed parts on both sides to a superficial tanning.

In testimony that I claim the foregoing as my invention, I have signed my name.

FELICE GILARDINI.
